UNITED STATES PATENT OFFICE

2,307,976

BANDING MACHINE

Rudolph Walz, Jersey City, N. J., and Henry A. Stone, New York, N. Y.

Application June 16, 1941, Serial No. 398,306

36 Claims. (Cl. 216—55)

This invention relates to banding machines and, more particularly, to automatic machines for applying bands or labels to frankfurters or other sausages.

The purpose of the present invention is the provision of an efficient and commercially practical automatic machine for applying bands to frankfurters or other sausages. As frankfurters are more or less flaccid, there are certain difficulties to be overcome, especially in respect to feeding the frankfurters properly to the machine and more particularly to the banding mechanism thereof, and also in respect to maintaining the frankfurters in proper condition for the securing of the bands thereto. These and other difficulties have been obviated in accordance with the present invention, and in the machine embodying the same.

It is also an object of this invention to provide a machine of the designated class having provision for applying bands to one of a plurality of connected or linked frankfurters or other sausages. More particularly, the frankfurter which is to have a band applied thereto and which is connected or linked to another frankfurter is conveyed as a unit with the latter to the banding station or position of the machine, a band is applied to one of the linked frankfurters at said station, and thereafter said linked frankfurters are conveyed as a unit to a discharge or delivery station or position of the machine.

The above and other objects, features and advantages of the invention will be more particularly apparent from the following description considered in connection with the accompanying drawings.

In the drawings:

Fig. 1 is a perspective view of the machine embodying the present invention;

Fig. 2 is a diagrammatic top plan view of the conveyor assembly;

Fig. 3 is a detail sectional view on the line 3—3 of Fig. 1;

Fig. 4 is a sectional view on the line 4—4 of Fig. 1, with parts omitted;

Fig. 5 is a sectional view on the line 5—5 of Fig. 6;

Fig. 6 is a sectional view on the line 6—6 of Fig. 1;

Fig. 7 is a detail sectional view on the line 7—7 of Fig. 6;

Fig. 8 is a sectional view on the line 8—8 of Fig. 7;

Fig. 9 is a fragmentary perspective view of the 55

supply and transfer conveyors at the adjacent parts of the two conveyors;

Fig. 10 is a fragmentary side view of the transfer conveyor;

Fig. 11 is a front perspective view of the band-applying mechanism and of certain parts associated therewith;

Fig. 12 is a side perspective view of the band-conveyor of the band-applying mechanism;

Figs. 13 to 15 are sectional views on the lines 13—13, 14—14, and 15—15, respectively, of Fig. 12;

Fig. 16 is a rear view, in elevation, of the band-applying mechanism;

Fig. 17 is a view similar to Fig. 16, with the parts thereof in a different operating position and with certain portions broken away for the purposes of illustration;

Fig. 18 is a sectional view on the line 18—18 of Fig. 17;

Fig. 19 is a sectional view on the line 19—19 of Fig. 12;

Fig. 19A is a view on the line 19a—19a of Fig. 19;

Fig. 20 is a perspective view of a banded sausage and of part of a companion unbanded sausage joined thereto;

Fig. 21 is a sectional view of a sausage with the band partially applied thereto and illustrates the condition in the stage of operation of the banding mechanism shown in Fig. 17;

Fig. 21A is similar to Fig. 21 but shows the overlapped ends of the bands pressed together by the heated presser member;

Fig. 22 is a view along lines 22—22 of Fig. 23 and shows the band-crimping device;

Fig. 23 is a side view partly in elevation and partly in section of parts of the band feeder, being taken on line 23—23 of Fig. 26;

Fig. 24 is a view partly in elevation and partly in section along lines 24—24 of Fig. 26;

Fig. 25 is a detail view on the line 25—25 of Fig. 24;

Fig. 26 is a perspective view showing the main cam shaft and parts of associated mechanisms;

Fig. 27 is a view partly in elevation and partly in section on the line 27—27 of Fig. 26;

Fig. 28 is a sectional plan view on the line 28—28 of Fig. 23;

Fig. 29 is a view partly in elevation and partly in section along the line 29—29 of Fig. 26;

Fig. 30 is a view in elevation with parts in section, taken along the lines 30—30 of Fig. 29;

Fig. 31 is an enlarged detail view;

Fig. 32 is a view of a mechanism taken along

line 32—32 of Fig. 29 and showing also certain parts operatively associated with said mechanism;

Fig. 33 is a sectional view on the line 33—33 of Fig. 45;

Fig. 34 is a sectional view on the line 34—34 of Fig. 45;

Fig. 35 is a sectional view on the line 35—35 of Fig. 11;

Fig. 36 is a sectional view on the line 36—36 of Fig. 35;

Fig. 37 is a sectional view on the line 37—37 of Fig. 11;

Fig. 38 is a view in elevation of one side of the machine;

Fig. 39 is a perspective view of the clutch mechanism;

Fig. 40 is a side view, partly in section, of the clutch, showing the disengaged condition thereof;

Fig. 41 is a view similar to Fig. 40, showing the engaged condition of the clutch;

Fig. 42 is a detail sectional view on the line 42—42 of Fig. 40;

Fig. 43 is a sectional view on the line 43—43 of Fig. 40;

Fig. 43A is a detail view, on a larger scale, of part of the clutch mechanism;

Fig. 44 is a block diagram of the pneumatic circuit;

Fig. 45 is a sectional view on the line 45—45 of Fig. 11;

Fig. 46 is a sectional view on the line 46—46 of Fig. 45;

Fig. 47 is a sectional view on the line 47—47 of Fig. 46;

Fig. 48 is a sectional view on the line 48—48 of Fig. 47;

Fig. 49 is a sectional view on the line 49—49 of Fig. 46;

Fig. 50 is a top plan view on the line 50—50 of Fig. 33.

Referring now to the drawings in further detail, the banding machine comprises, in general, a frame having a main central section 10, means for applying bands to the articles, including a band-wrapping device or applying mechanism 14 forming part of the band-applying means, means 15 (Fig. 12) for feeding bands to the band-wrapping device, a supply conveyor 16 operatively supported on the lateral section 18 of the frame; a conveyor and article holder 20 which transfers the articles to be banded from the conveyor 16 and presents said articles successively to the band-applying means and holds the articles while the bands are applied, and which thereafter moves the banded articles from said band-applying means to a delivery position, and a discharging conveyor 22 operatively supported on the lateral section 24 of the machine frame. The machine embodying the present invention in the form illustrated herein is designed to apply bands to one of a set of two joined or linked frankfurters. The bands or labels are of the thermoplastic-adhesive coated type, and means for applying heat and pressure to the wrapped bands is provided for securing the ends of the bands together when wrapped about the articles.

The several main parts of the machine will now be described more specifically.

The sausage conveyors and holders

The supply conveyor 16 is of the endless belt type and comprises three laterally spaced belts or sprocket chains 26, 28 and 30, indicated more or less diagrammatically in Fig. 2 and struc-

turally in Figs. 4 to 8. Said conveyor chains are composed of the necessary sprocket chain links which engage and are driven by the usual sprocket wheels. The sprocket chain conveyors are provided with pocket-forming members 32 secured to certain of the links by individual brackets 34. The two frankfurters of the set are carried by the three chains of the conveyor, as illustrated in Fig. 6, the frankfurter F to which the band is to be applied being carried by chain 26 and the companion frankfurter Fc of the set being carried by chains 28 and 30 in alignment with frankfurter F. The upper reach of chain 26 is supported on a longitudinally extending bar 36 which extends for the full length of frame section 18, and the upper reaches of chains 28 and 30 are supported on longitudinally extending bars 38 and 40, respectively, carried by a cover plate 42 which rests on the longitudinally extending top portions 44 and 46 of frame section 18 in movable relation laterally of the frame (Fig. 6). Longitudinally extending rails 47 and 49 are disposed in stationary position at opposite sides of the upper reach of chain 26 for supporting the frankfurters carried by said chain, said frankfurters sliding longitudinally of said rails during movement of said chain.

As the frankfurters or other articles may vary in length, provision is made for adjusting the space between chain 26 and chains 28 and 30. For this purpose the adjusting mechanism will now be described as provided with particular reference to Figs. 4, 5, and 6. Said mechanism comprises a screw-threaded rod 48 journaled at its ends in the longitudinally extending stationary frame members 50. A threaded member 52 is engaged by rod 48 and is held against rotation thereon by the connection of said member 52 with plate 42, whereby rotation of said rod causes movement of member 52 longitudinally of the rod and thus moves plate 42 laterally of frame section 18 in either direction depending upon the rotation of rod 48. The sprocket wheels at both ends of chains 28 and 30 are mounted for unitary adjustment on stationary shafts 54 and 56, said first mentioned shaft 54 being illustrated in Fig. 4 and said last mentioned shaft 56 being illustrated more or less diagrammatically in Fig. 2. The manner of adjusting the sprocket wheels on said shafts is substantially the same for both ends of the chains, except that shaft 56 is the driving shaft and the sprocket wheels are splined thereto while the sprocket wheels on shaft 54 are freely rotatable thereon. Therefore, only the mechanism associated with the wheels on shaft 54 need be specifically described. Accordingly, referring to Fig. 4, it will be observed that sprocket wheels 58 and 60 of companion chains 28 and 30 are integral with each other or are otherwise arranged in fixed or unitary relation having as here shown a central connecting portion 62 provided with a peripheral groove 64. A fork 66 is fixed to threaded member 52 and engages connecting member 62 in said groove 64 whereby movement of threaded member 52 causes movement of sprocket wheels 58 and 60 longitudinally of shaft 54 toward and away from sprocket chain 26. As indicated in Fig. 2 shaft 56 has associated therewith an adjusting rod 48a which is constructed and operates in the same way as rod 48 and which it will be understood has similar mechanism associated therewith. Rods 48 and 48a are provided with sprocket wheels 68 and 70, respectively, connected to each other by a sprocket chain 72

whereby rotation of rod 48a results in a corresponding rotation of rod 48 and an equal lateral adjustment of the sprocket wheels on shafts 54 and 56. Rod 48a is also provided with a sprocket wheel 74 operated by a sprocket chain 76 actuated by a sprocket wheel 78 operated by a manually operable crank 80. Thus by turning crank 80 chains 28 and 30 of conveyor 16 can be easily adjusted as a unit toward and away from chain 26, to adjust the distance between the chains according to the length of the frankfurters. It will be observed that the sprocket wheels 82 and 82a are also mounted on shafts 54 and 56, respectively, said mounting as to sprocket wheels 82 on shaft 54 being illustrated in Fig. 4. As here shown sprocket wheel 82 is positioned between the bearing portion 50a of frame member 59 and collar 84 fixed to shaft 54. Shaft 54 is secured against movement by nuts 86 and 88 engaged on the threaded end portion 90 of said shaft and in engagement with the opposite sides of longitudinally extending frame member 92.

Shaft 56 is a driven shaft for driving the sprocket wheels of the chain conveyor 16, and for this purpose shaft 56 unlike shaft 54 is mounted for rotation in bearing 50c and 50d (Fig. 2) in frame members 50. Shaft 56 is driven by a sprocket wheel 94 actuated by a sprocket chain 96 which engages a sprocket wheel 98 fixed to a driving shaft 99. Said last mentioned shaft 99 is operatively connected through suitable gearing for actuation by a shaft 100. Shaft 99 also operates discharge conveyor 22 which as illustrated in Figs. 1 to 3 comprises a plurality of laterally extending plates 102 carried by the links of two sprocket chains 104.

The frankfurters or other articles to be banded are presented by conveyor 16 to the receiving end of article conveyor and holder 20. Conveyor 20 comprises a pair of sprocket chains 106 and 108 which receive the frankfurter F of the set from chain 26 of conveyor 16, and a sprocket chain 110 which receives the companion frankfurter Fc of the set from the pair of sprocket chains 28 and 30 of the supply conveyor 16. As sprocket chains 28 and 30 are laterally adjustable, sprocket chain 110 is also laterally adjustable toward and away from the companion pair of sprocket chains 106 and 108, for which purpose the sprocket wheels of chain 110 are adjusted laterally on the sprocket wheel shafts of conveyor 20 by screw-threaded rods 112 and 114 for which purpose crank 80 is operatively connected to rods 112 and 114 of the adjusting mechanism of chain 110 for adjustment of the latter simultaneously with the adjustment of companion chains 28 and 30 of conveyor 16. For this purpose, sprocket wheel 78 is fixed to the end of rod 114 and a sprocket wheel 113 is fixed to the end of rod 112, said sprocket wheels being operated by chain 76. A member 115 (Fig. 48) holds chain 76 in engagement with sprocket wheel 113. The mechanism for adjusting chain 110 is similar to that for adjusting chains 28 and 30 of conveyor 16. Thus, as illustrated in Figs. 46, 47 and 48, a nut 117 is threaded on rod 112 and has a forked member 119 fixed thereto and projecting transversely therefrom, the laterally spaced ends 121 of said forked member being disposed at opposite sides of sprocket wheel 138 of chain 110 at the adjacent end of the conveyor. Said ends 121 of the forked member have upper extensions 123 which are fixed to the movable plate 125 of the frame for moving said plate laterally when sprocket wheel 138 is moved laterally 75

of shaft 146. It will be understood a similar mechanism is associated with rod 114 and the adjacent shaft at the opposite or delivery end of conveyor 20 so that both ends of chain 110 and plate 125 are adjusted equally toward and from chains 106 and 108 when crank 80 is operated. Further, it will be observed that chains 28 and 30 are simultaneously adjusted when crank 80 is operated, the movement of said last mentioned chains toward and from chain 26 being equal to the movement of chain 110 toward and from chains 106 and 108.

As the sprocket chains and article holders of conveyor 20 are of the same construction a description of only one of said chains and of the article holders carried thereby is needed. By reference to Figs. 9 and 11 it will be observed that each sprocket chain of conveyor 20 is provided with means for gripping and holding the frankfurters or other articles applied thereto by conveyor 16. The article holding and gripping means are more clearly illustrated in Fig. 10 and by reference thereto it will be observed that said means comprises a pair of chain links 116 and 118 connected to an intermediate chain link 120. Companion links 116 and 118 are provided with fingers 122 and 124 pivotally mounted thereon by means of pivot pins 126 and biased for movement toward each other by springs 128 to a maximum extent limited by the engagement of pins 130 on said fingers with shoulders 132 formed on each of the opposite sides 134 of links 116 and 118. The intermediate link is provided with an article seating portion 136. It will be understood that when the frankfurter or other article is placed in position said article is gripped by the spring pressed companion fingers 122 and 124 of each holder on the chain carrying the same, it will be noted that as the portion of the chain which carries the holder passes around the sprocket wheel 138 companion links 116 and 118 of the holder are moved in such manner as to spread said fingers 122 and 124 to permit the insertion of the article therebetween, and that thereafter when the holder moves past the sprocket wheel said fingers 122 and 124 converge toward each other and grip the article therebetween. Links 120 are connected pivotally to companion links 116 and 118 by pins 127 each of which carries a roller 129. In passing from sprocket wheel 138 toward the banding mechanism chains 106 and 108 are supported by longitudinal rods 131 and 133, respectively, (Fig. 34), provided to rigidly support the article holder at the banding station as considerable pressure is applied thereto by a part of the band-applying mechanism. Beyond the banding station, said chains are supported by laterally spaced longitudinal plates 135 which provide room for the action of parts of the banding mechanism and associated parts of the machine. Plates 137, which are shown in section in Fig. 33, engage rollers 129 at the top thereof and thereby prevent upward movement of the chain links which might otherwise occur due to the action of the springs 128, and which would result in opening movement of the companion gripper fingers 122 and 124. It will be understood that hold-down plates 137 extend longitudinally for substantially the full length of conveyor 20. When the holder reaches the delivery end of conveyor 20 for discharge of the articles on the discharge conveyor 22 said holder passes with the chain over the sprocket wheel 140 to permit the article to drop from said holder onto the belt of the discharge conveyor. Arms 142 are pro-

vided adjacent the discharge end of conveyor 20 for guiding the banded articles on the discharge conveyor.

Provision is made for transferring the frankfurters or other articles from the supply conveyor 16 to the conveyor and article holder 20. For this purpose two sets of transfer fingers 144 and 145 engage the frankfurter to be banded and the companion frankfurter, respectively, at the delivery end of conveyor 16, and move the same upwardly and place them between the spread fingers 122 and 124 on the chains of the conveyor 20, after which said fingers are retracted to a position for engaging the next set of frankfurters brought to the delivery end of conveyor 16. Fingers 144 and 145 are for this purpose mounted upon the sprocket wheel shaft 146 at the receiving end of conveyor 20 (Figs. 30, 45, 46, 48 and 49). More particularly, said fingers 144 are carried by a sleeve 148 pinned to shaft 146 and thereby held against movement longitudinally of the shaft. Said sleeve is provided with a gear segment 150 which meshes with a gear segment 152 carried by the lever 154 which forms part of an actuating mechanism hereinafter to be described. As shown, fingers 144 project in laterally spaced relation from sleeve 148. Oscillation of said sleeve and of the fingers carried thereby results in oscillation of shaft 146, but this does not affect the rotation of sprocket wheels 138 since the latter are freely rotatable on said shaft. Fingers 145 are oscillated by shaft 146 simultaneously with fingers 144. By reference to Figs. 46 and 49, it will be observed that fingers 145 are located at opposite sides of sprocket wheel 138 of laterally adjustable chain 110. Each finger 145 has a sleeve portion 147 which is splined to said shaft by the integral part 149 which engages in the longitudinally extending spline groove 149a of said shaft. The sleeve portions 147 of fingers 145 are positioned at the opposite sides of sprocket wheel 138 of chain 110 and the adjacent ends 121 of forked member 119 and are thus moved laterally with chain 110 when the latter is adjusted longitudinally of shaft 146 toward and away from chains 106 and 108. Gear segment lever 154 for oscillating fingers 144 and 145 is actuated under the control of cam 155 fixed to and rotated by shaft 190, and for this purpose said gear segment lever is connected by an adjustable link 157 to the pivot lever 159 having the cam follower roller 161. Link 157 is pivotally connected at its opposite ends to lever 159 and to the reflexed arm portion 163 of gear segment lever 154. A tension spring 165 holds cam follower roller 161 in engagement with cam 155, and another tension spring 167 connected to arm 163 of lever 154 resiliently opposes movement of said lever in one direction, that is, in a direction for causing upward movement of fingers 144 and 145 and assists in the retraction of said fingers.

Conveyor 20 is operated intermittently for moving the articles to be banded in succession from the supply container 18 to bring said articles to the band-applying means and for thereafter moving the banded articles from the position at which the bands are applied thereto to the position for delivering the banded articles to the discharge conveyor 22. The supply conveyor 16 and the discharge conveyor 22 are operated continuously during the operation of the machine, while the conveyor and article holder 20 is actuated intermittently in timed relation to supply conveyor 16. The means for actuating conveyor 20 intermittently will be described in connection with the

operation of the band-applying means as said intermittent operation of conveyor 20 is directly related to the operation of the band-applying means.

The band-applying means

The band-applying means is indicated generally at 14 (Fig. 1) and is more particularly shown in Figs. 11, 12 and 16 to 18. Said device comprises a movable frame 156 carried by a movable rod 158 which is guided for vertical movement in the guide bearing portion 160 of the stationary head 162 of the main frame, the lower end of rod 20 being guided by the bearing portion 164 (Fig. 27) of the main frame. The construction and operation of the band-applying device 14 will best be understood by reference to Figs. 11, 12 and 16 to 21A. Said device includes an arm 166 pivotally mounted on a pin 168 projecting forwardly from frame 156, and a companion arm 170 fixed to a shaft 172 journaled for rotation in the bracket portion 174 of frame 156. A tube 176 is mounted for vertical movement in guide bearing portions 178 and 180 of movable frame 156. Said tube is projected downwardly by a spring 182 and carries at its lower end a flat plate or platen 184 which is provided with an aperture in registry with the bore of tube 176. Tapes 186 and 188 are attached to plate 184 and engage over fingers 190 and 192 pivotally mounted at the lower ends of arms 166 and 170, respectively. Said tapes are held in taut condition by tension springs 194 and 196, respectively, connected at their upper ends to arms 166 and 170, respectively. A lever 198 is fixed to shaft 172 for turning the latter and thereby turning arm 170. A spring 200 is connected to one arm 202 of lever 198 and tends to turn the same arm in a clockwise direction (viewing Fig. 16). The other arm 204 of lever 198 is engaged by an arm 206 fixed to a shaft 208 journaled for turning movement in the bearing portions 210 of frame 156. A stop 212 limits the movement of lever 198 in a counter-clockwise direction, while movement of lever 198 in a clockwise direction is controlled by arm 206, said last mentioned movement being effected by spring 200. The upper end of arm 166 is pivotally connected to one end of a slotted link 214. The other end of link 214 is pivotally connected to an arm 216 which is fixed to and turned by a shaft 218 journaled for said turning movement in bearing portions 220 and 222 of the rearwardly projecting portion 224 of frame 156. Block 226 is slidably movable in the slot of link 214 and is pivotally connected to arm 170 by the pivot screw 228.

Arm 170 is actuated by lever 198 first for moving said arm to the position shown in Fig. 16 under the control of arm 206 when the latter moves in a counter-clockwise direction, after which arm 216 is moved in a counter-clockwise direction for actuating arm 166 for bringing the latter from the position illustrated in Fig. 16 to the position illustrated in Fig. 17, and during this movement the block 226 in the slot of link 214 is engaged by the right hand end of said slot viewing Figs. 16, 17 and 18 thus turning lever 198 in a counter-clockwise direction thereby to move arm 170 from the position illustrated in Fig. 16 to the position illustrated in Fig. 17. This results in the band B being applied to and wrapped around the frankfurter F as illustrated in Fig. 21. The upward movement of heated presser member 230 (Fig. 11) then takes place whereby said member engages the end portions B1 of

the band and presses the same against end portion B2 of the band for connecting said ends together in overlapped relation, as illustrated in Fig. 21A, the heat of said presser member softening the thermo-plastic coating on the inner surface of end portion B1 for rendering said coating adhesive. The construction and operation of presser member 230 will be hereinafter described in further detail.

The movements of shafts 208 and 218 for the actuation of arms 166 and 170 is accomplished by the mechanism which will now be described with reference more particularly to Figs. 12, 26 and 27. Shafts 208 and 218 have fixed thereto at their rear ends arms 232 and 234, respectively. A downwardly extending link 236 is pivotally connected to arm 232 and a downwardly extending link 238 is pivotally connected to arm 234, and the lower ends of said links 236 and 238 are pivotally connected to levers 240 and 242, respectively. Said levers are mounted for turning movement on a shaft 244 disposed below the cam shaft 246 (Fig. 26) in the casing of central frame portion 16. Levers 240 and 242 are held in retracted position by springs 248 and 250 and are provided with rollers 252 and 254, respectively, which engage companion cams 256 and 258, respectively, but only when rod 158 is in its lower position at which time plate 184 of the band-wrapping device is in engagement with the frankfurter or other article in the wrapping position. Vertical movement of rod 158 is accomplished by cam 260 and the mechanism associated with said cam and with said rod 158. Said last mentioned mechanism comprises a follower arm 262 provided with a roller 264 engageable with cam 260. Said arm 262 is mounted for turning movement on a fixed shaft 266 and is pivotally connected at its other end to a link 268 which is connected to rod 158 by a connecting member 270 fixed to the lower end of said rod and pivotally connected to the lower end of said link. Rod 158 is releasably held in the retracted and lower position thereof by a tension spring 272 which is also effective to hold cam lever 262 at the roller 264 thereof in engagement with cam 260. It will be understood that in the actuation of the machine when main cam shaft 246 is rotated cam 260 is effective to depress rod 158 for moving frame 156 downwardly thereby to bring the platen 184 of the band-wrapping device into engagement with the frankfurter or other article at the wrapping station, after which links 236 and 238 are actuated by their companion cam controlled levers 240 and 242, respectively, for turning shafts 208 and 218 whereby to operate the arms of the band-wrapping device.

The operation of the heated presser member 230 which acts in conjunction with the band-wrapping device and forms a part of the band-applying means will now be described, reference being had more particularly to Figs. 11, 29, 30, 32, 33 and 50, and at the same time the intermittent operation of conveyor 20 will be described. Presser member 230 is carried by a base 274 in which an electric heating element (not shown) is provided. Said base 274 is fixed to brackets 276 carried by arms 278 pivotally mounted on a transverse shaft or rod 280 mounted at its ends in members 282 which slidably engage longitudinally extending guides 284 of the machine frame, said rod 280 and slideable members 282 forming a cross-head. The intermediate portion of shaft 280 of said cross-head is connected by means of a link 286 to a lever 288, one end of said link hav-

ing a pivotal bearing on said shaft and the opposite end of said link being pivotally connected to lever 288 by a pin 289. A lever 290 is connected by means of a link 292 to brackets 276, one end of said link having a pivotal bearing on a pin 293 connecting said brackets and the opposite end of said link being pivotally connected to said lever. The operation of levers 288 and 290 imparts to presser member 230 an up and down movement, that is, a movement toward and away from the band-wrapping device, and also a movement in the direction of the chains of conveyor 20 toward the delivery end of said conveyor and a movement in a direction opposite to said last mentioned movement, the path of movement of member 230 being indicated by the dot and dash lines at 294 in Fig. 32. As a result of this movement heated presser member 230 is brought into engagement with the outer end portion B1 of the wrapped band and remains in said engagement while the conveyor 20 moves the wrapped article from the wrapping position a predetermined distance toward the discharge conveyor, after which presser member 230 is moved downwardly and then in a direction opposite to the delivery movement of conveyor 20 to a retracted position ready to be moved upwardly for engaging the next wrapped article. Moreover, during the movement of presser member 230 in engagement with the wrapped article for the predetermined distance referred to, the movement of the conveyor chain is accomplished by the engagement of hooked members 296 carried by brackets 276 with links of the conveyor chains 106 and 108, said hooks being disengaged from the chain links when the heated presser member 230 is retracted from engagement with the wrapped bands. Hold-down plates 131, hereinbefore referred to, by engaging rollers 129, maintain the conveyor chains in engagement with hooked members 296 and thereby prevent the conveyor chains from slipping off said hooked members which might otherwise happen, in the rapid chain movement, if the chain links were permitted to move upwardly. As the sprocket wheels 140 of each conveyor chain are keyed to shaft 146, all chains at said conveyor are operated together in unison. When the heated presser member is thus retracted the wrapped band is engaged by a second presser member 298 (Figs. 30 and 31), constituted by a lever 300 pressed upwardly by a spring 302 for holding the overlapped end portions B1 and B2 of the band in engagement with each other under pressure so that the thermoplastic adhesive can cool sufficiently to become set.

Lever 288 is actuated by a cam-operated lever 304 provided with a cam follower roller 306 engaged by a cam 308 rotated by shaft 100. One end of lever 304 is engaged by a spring 310 which holds roller 306 in engagement with cam 308, and the other end of said lever 304 is provided with a roller 312 which engages one arm of lever 288 in a slot 314. Lever 290 which actuates link 292 for moving heated presser member and hooks 296 to the projected and retracted positions thereof is actuated by a cam 316 rotated by shaft 100. For this purpose cam lever 290 is provided with a roller follower 318 which engages cam 316. A spring 320 is connected to the outer end of cam lever 290 for holding the follower roller 318 in engagement with cam 316 and for moving presser member 230 and hook member 296 to retracted position under control of said cam 316. Shaft 100 is rotated in timed relation to main cam shaft 246 by gears 322 and 324 fixed to shafts 246 and

100, respectively (Figs. 26 and 29). Likewise supply conveyor 16 is operated in timed relation to the main cam shaft 246 since, as described above, said conveyor is operated by shaft 160 for which purpose said shaft 100 is provided with a gear 326 fixed thereto and engageable with a companion gear 328 connected to shaft 99 (Figs. 2, 26 and 29).

Provision is made for holding conveyor 20 stationary during the band-wrapping operation. For this purpose the locking device illustrated in Fig. 30 is provided. Said locking device comprises a locking disk 330 mounted on and fixed to shaft 147 of said conveyor, which shaft is located at the delivery end of the conveyor. Said locking disk is provided with circumferentially spaced radially extending slots 332 in which a locking pin 334 is projected at the time the article holder is in band-wrapping position, i. e., below band-wrapping device 14. Locking pin 334 is slidable in a 20 guide member 336 and is urged to retracted position by a tension spring 338, the inner end of said pin being thereby held resiliently in engagement with a cam 340 fixed to and rotatable by shaft 100. It will be understood that the operation is such that when the article to be banded is presented at the band-wrapping station pursuant to the movement of conveyor 20, as described above, for presenting the article to the band-wrapping device, locking pin 334 projects into one of slots 332 and thereby prevents turning of shaft 147 and consequently prevents movement of the chains of conveyor 20 and holds the latter and thereby holds the article holder stationary during the banding operation.

As the present machine is intended primarily for applying bands to frankfurters and as the latter are curved longitudinally, it is advisable to provide means for pressing the frankfurters in the holders therefor downwardly into firm engagement with the supporting plate 120 of the holder. For this purpose there is provided a plate 342 (Fig. 11). Said plate is carried by the lower end of a rod 344 mounted for sliding movement in upper and lower frame portions 345 and 348. Rod 344 and the plate 342 carried thereby are thus movable toward and away from the frankfurter when frame 156 is lowered and raised, respectively, whereby to allow movement of the article holders by the conveyor. Said rod is also urged downwardly by a compression spring 350 thereby to press plate 342 firmly against the frankfurter in the article holder when the latter is positioned below said plate. For preventing turning movement of rod 344 and of the plate 342, said rod is fixed to a member 352 which is also fixed to the upper end of a pin 354 slidable in frame portion 346.

The band supply and feeding means

The bands which are to be applied by the band-wrapping device are held in stacked relation in an adjustable holder 356 (Figs. 12, 19 and 19A). Said holder comprises spaced vertical members 358 provided at their lower ends with shelves 360 and 361 on which the opposite end portions of the bands rest and by which the bands are supported in stacked relation. Members 358 are adjustable toward and away from each other in order to accommodate bands of different lengths. The adjusting means comprises, as shown more clearly in Fig. 28, slidable blocks 362 which carry said members 358, and a screw-threaded rod 364 which is in threaded engagement with blocks 362 and which upon turn-

ing movement thereof by knob 366 is effective to move said blocks and thereby said holders 358 toward and away from each other. The holder is also adjustable as a whole laterally, that is, in the direction of movement of conveyor 20, and the means provided for this purpose comprises a sliding block 368 having a yoke 370 which engages rod 364 between the spaced collars 372 fixed to said rod. Block 368 is moved longitudinally by a rod 374 fixed thereto and projecting through the side of the housing 376. The outer end portion 378 of rod 374 is threaded and is engaged by a nut 380 held against longitudinal movement on said threaded end portion whereby rotation of said nut is effected to cause longitudinal movement of said rod. Rod 364 is held by yoke 370 against longitudinal movement, except when block 368 is moved, whereby rotation of said rod is effective to move blocks 362.

Band holder 356 is also adjustable for bands of different widths. For this purpose a set of fingers 382 is provided at each end of the holder and near the top and bottom thereof. The lower and upper companion fingers of each set are carried by vertical rods 384 which are mounted for turning movement about their longitudinal axes, respectively, so that by turning said rods 384 the companion fingers 382 can be moved toward and away from each other. The lower and upper fingers 382 are connected to each other at opposite sides of the holder by vertical members 386 which, as illustrated in Fig. 19, engage the opposite side edges, respectively, of the bands. Fingers 382 are adjusted by the operation of the nut 388 which engages a screw-threaded rod 390 for moving the latter longitudinally, nut 388 being held against longitudinal movement by retaining member 392. Screw 390 has collars 394 fixed thereto, said collars being pivotally connected to yoke portions 396 provided at the outer ends of lower fingers 382. Collars 394 are in threaded engagement with rod 390 whereby they are caused to move longitudinally of said rod when the latter is turned by operation of nut 388. A locking nut 399 is provided on rod 390 for holding the parts in adjusted position.

The means for feeding the bands from holder 356 to the band-wrapping device 14 will now be described with reference more especially to Figs. 12, 23 and 24. Said means comprises a conveyor indicated generally at 400 in Figs. 12 and 23. Said conveyor comprises a carriage 402 mounted for longitudinal movement toward and away from band-wrapping device 14 in a guide 404. A suction picker device 406 is pivotally mounted on carriage 402 by a pivot pin 408. A tension spring 410 connected to carriage 402 and to suction picker 406 urges the latter downwardly toward carriage 402. Said suction picker is provided with a band picker plate 412, the forward end of which is adapted to engage the lowermost band and to separate the same from the stack when the suction picker is actuated in the manner hereinafter described. Picker plate 412 is positioned to engage the band in an off-center position thereof, that is, at an area somewhat closer to one end of the band than to the other end thereof, so that when the band is applied to the article with its ends overlapping, the printing thereon will be disposed centrally of the wrapped band. In order to prevent one end of the band, which is engaged by the picker at the off-center position thereof, from remaining on its supporting shelf 360 of the band holder, said shelf is located, as illustrated in Fig. 19A, at a somewhat

higher level than shelf 361 which supports the other end of the band. This arrangement of shelves 360 and 361 results in both ends of the band being removed from the stack substantially simultaneously during the band-removal operation of the suction picker.

A fluid passage 413 is provided in said suction picker and communicates with a nipple 414 which is connected to a source of vacuum. Carriage 402 has a rack 416 fixed thereto and engaged by a pinion 418 for moving carriage 402. Pinion 418 is fixed to a shaft 419 which has a gear 420 fixed thereto for turning it. Gear 420 meshes with a gear segment 421 fixed to a lever 422. Lever 422 is actuated by cam 424 which is rotated by the main cam shaft 246, said lever 422 having an arm 426 provided with a cam follower roller 428. The pivot pin for gear segment lever 422 is indicated at 430. The tension spring 432 is connected to lever 422 for holding cam follower roller 428 in engagement with the controlling cam 424 and for resiliently opposing movement of said lever of said cam.

As stated above, suction picker 406 is moved downwardly by spring 410. Upward movement of said suction picker about its pivot 408 takes place during the longitudinal movement of the suction picker with carriage 402. For this purpose said suction picker is provided with a roller 434 carried at one side thereof in position to engage the upper part 436 of an arm 438. A cam actuated lever 440 pivoted on a pin 442 is connected to arm 438 for actuating the latter under the control of cam 444 rotated by the main cam shaft 246, said lever 440 having a cam follower roller 441 which engages said cam. The cam actuated lever 440 thus projects arm 438 into the path of movement of the suction picker when the latter is moved longitudinally and thereby causes the upward movement of suction plate 412 for bringing the apertured end thereof into engagement with the lowermost band of the stack. It will be observed that in the projected position of arm 438 the upper edge of said arm which is engaged by roller 434 on the suction picker is inclined upwardly in a direction to cause the proper upward movement of the suction picker plate 412.

When plate 412 is moved upwardly for engaging the lowermost band of the stack in holder 358, sufficient movement is imparted to said plate of the suction picker not only for this purpose but also for moving the entire stack of bands upwardly. This is done for the purpose of supporting the main body of bands of the stack, that is, for supporting all of the bands except a few of the lowermost bands, during the downward movement of picker plate 412 which results in the separation of the lowermost band from the holder whereby to relieve the weight of the stack of bands from supporting shelves 360 and 361 of the holder so as to facilitate the removal of the lowermost band from the holder. The means for holding the main body of the stack in raised position during the removal of a band by the suction picker comprises a pair of arms 446 provided with pointed upper ends 447 adapted to engage bands at one side of the holder and below the main body of bands and force the opposite side edges of the bands against the adjacent vertical members 386 of the holder. Stops 449 are provided on arms 446 in position to engage fingers 382 of the holder for limiting the movement of said arms toward the holder. The movement of arms 446 is accomplished under the control of cam 448 which is rotated by the main cam

shaft 246. Said cam actuates a lever 450 pivotally mounted on a pin 452 and provided with a cam follower roller 454. Member 450 is connected to a rod 456 provided at the opposite ends thereof with lifting blocks 458 (Fig. 25) fixed to said rod in position to engage links 460 which are pivotally connected to companion arms 462 for turning arms 466 toward and away from the adjacent side edges of the bands in holder 358.

After the band is separated from the stack by downward movement of the suction picker plate 412, the separated band is moved to a crimping device 464 (Figs. 22 and 23), for crimping the end portion B2 of the band as illustrated in Fig. 21 which is done for the purpose of facilitating overlapping of one end portion of the band by the other during the wrapping operation. The crimping device comprises a crimping plate 466 on which an end portion of the band is engaged and over which it is folded as illustrated in Fig. 22 by an arm 468 of the crimping device. Arm 468 is operated by a gear 470 which meshes with an actuating gear 472 turned by an arm 474. A spring 476 is disposed between arms 468 and 474 for moving crimping arm 468 to retracted position. Arm 474 is engaged by an actuating member 478 fixed to push rod 480. A cam 482 is rotated by the main cam shaft 246 for controlling the operation of the crimping device, and for this purpose actuating rod 480 is connected to the cam actuated lever 484 which is pivoted at 486 and which is provided with a cam follower roller 488 engaged by said cam 482. A tension spring 490 holds the cam follower roller 488 in engagement with cam 482 and resiliently opposes upward movement of actuating rod 480 of the crimping device. A guide member 492 is provided between the band stack holder 356 and the crimping device 464 for guiding the separated band to position in relation to crimping plate 466.

After the band is crimped by crimping device 464 it is transferred by movement of the suction picker with carriage 402 to a temporary holder 494 (Figs. 12 and 14). Said holder is mounted in stationary position between the crimping device and the band-applying mechanism 14 and is carried by a tube 496 clamped in a bracket 498 fixed to the stationary head 160 of the machine frame. Holder 494 is provided with openings 499 in communication with the bore of tube 496 for the application of suction to the band transferred to said holder by the suction picker. Means are provided for transferring the band from temporary holder 494 to the band-applying mechanism 14, said means comprising a plate 500 carried by tubes 502 fixed to the body of carriage 402. Plate 500 is provided with openings 504 in communication with the bore of tubes 502 for applying suction to the band carried by said plate. Said tubes 502 communicate with a passage 506 in carriage 402, said passage terminating in a nipple 508 for connection with an air tube leading to a source of vacuum.

In the operation of the means for feeding the bands to the banding mechanism, the carriage 402 is moved from the initial position shown in Fig. 12 in a direction toward the band stack holder 356 to the position illustrated in Fig. 23. When in this position the suction picker is moved upwardly about its pivot 408, by the engagement of roller 434 with upper part 436 of arm 438, the movement resulting in the engagement of the forward end of suction picker plate 412 with the bottom of the stack and in the raising of the

stack of bands by picker plate 412 upwardly in holder 358. When this occurs arms 446 associated with the stack holder engage the stack of bands as described above and hold the latter in raised position, with the exception of a few of the bands at the bottom of the stack which drop upon the supporting shelves 360, 361 of the holder. The downward movement of suction picker plate 412 then occurs and the lowermost band is separated from the other bands in the stack and removed from the holder. Then the carriage moves toward the banding mechanism and the removed band carried by the suction picker plate 412 is presented to the crimping device 464 which operates to crimp the edge of the band as illustrated in Fig. 22. After crimping of the band, the carriage moves in the same direction, that is, toward banding mechanism 14, and the crimped band, still held on picker plate 412, is transferred by the latter to the temporary holder 494. In the meantime, that is, during the transfer of the band by the picker plate 412 from the crimping device to the temporary holder 494, plate 500 of the band feeding means had removed a previously crimped band from said holder 494 and had conveyed the same to the suction plate or platen 184 of the banding mechanism. The cycle of movement of carriage 402 is completed by the retraction of plate 500 from the banding mechanism immediately after the band is transferred to plate 184 of the banding mechanism.

The source of suction is a vacuum tank 510 (Fig. 38) exhausted to the required degree by a suction pump 512 operated by the shaft 514. Said shaft is rotated by a pulley 516 operated by a belt 518 connected to the machine operating motor M. Said motor is carried by an adjustable support 520 pivotally mounted as at 522 to the central frame section 10 and provided with an adjusting screw 524. The application of suction to the several suction devices is controlled by a main control valve 530 of any suitable construction. Said valve is actuated by a rod 528 (Fig. 26) under the control of a cam actuated lever 530 pivotally mounted on a pivot pin 532. Said lever 530 is operated by cam 534 which is rotated by shaft 180. It will be understood that valve 526, which need not be described in detail as it does not form per se part of the invention, operates to supply and cut off suction at the proper times to the various suction operated devices. More particularly, it will be understood that suction is applied simultaneously to the picker plate 412 and to the conveyor plate 500, and that suction is cut off from temporary holder 494 when plate 500 engages the band on said holder for transferring the band to the band-applying device 14. Likewise, it will be understood that suction is cut off from picker plate 412 and from plate 500 and is at that time applied to temporary holder 494 and to the plate 184 of the banding mechanism when the bands are transferred thereto by the picker plate 412 and by the conveyor plate 500, respectively. Also, it will be understood that suction is cut off from plate 184 as soon as said plate is lowered for the purpose of engaging the band carried thereby in the banding position preliminary to the wrapping operation of the banding mechanism.

Provision is made for preventing the feeding of bands to the banding mechanism in the event that a frankfurter is not in position at the delivery end of supply conveyor 18. The means provided for this purpose will now be described with reference to Figs. 11, 35 and 36 as well as to

the block diagram of the pneumatic circuit illustrated in Fig. 44. Said means comprises a valve 536 operable in a valve casing 538 having passages controlled by said valve in communication with valve 526 and the suction picker 406. Where there is a frankfurter at the delivery end of supply conveyor 18 as illustrated in Fig. 11 valve 536 is held in fluid circuit-opening position by the article feeler device 540 which is connected to valve 536 by a stem 542. The feeler device comprises rollers 544 and 546 carried by a U-shaped bracket 548 fixed to the lower end of stem 542. A tension spring 550 connected to the upper end of valve 536 and to a bracket 552 fixed to valve casing 538 urges valve 536 to closed position and closes said valve when there is no frankfurter in position at the delivery end of conveyor 18. A rod 554 is slidably in bracket 552 and is connected to a plate 556 fixed to and projecting from the lower end of valve 536, the purpose of this device being to prevent the rotation of said valve and of stem 542. Plate 556 is also arranged for engagement with and by a bar 558 fixed to and extending from the movable frame portion 348, for limiting the downward movement of the article feeler 540.

Power transmission and clutch

As explained above, shaft 514 is actuated by motor M. Said shaft 514 runs continuously as long as the motor is energized. Shaft 514 is arranged to drive shaft 244 under the control of a clutch illustrated in Figs. 38 to 43. Said clutch comprises a driving member 560 and a driven member 562, the latter being fixed to shaft 244 and the driving clutch member 560 rotating freely on said shaft unless the clutch is engaged. Driving clutch member 560 includes a sprocket wheel 564 which is connected to and driven by shaft 514 through sprocket wheel 566 and sprocket chain 568. The clutch is controlled by the hand lever 570 which, when in the position illustrated in Fig. 40, is effective to disengage the driving clutch member 560 from the driven clutch member 562 and which, when moved to the position shown in Fig. 41 is effective to engage said driving clutch member with said driven clutch member. However, the clutch is of the type which remains engaged until the cycle of operations of the machine parts is completed, even though in the meantime control lever 570 is moved from the clutch engaging position shown in Fig. 41 to the clutch disengaging position shown in Fig. 40, so that when the machine is again started by operation of control lever 570 the parts of the machine will be in the correct position and relationship for the resumption of the proper operation of the machine. Lever 570 is held in either of two positions by a spring 571. The engagement of the driving and driven members of the clutch is accomplished through a dog 572 which slidably fits within an axially extending non-circular opening 574 in the driven clutch member and which is projected by a spring 576 for driven engagement in a non-circular opening 578 in driving clutch member 560 (Fig. 43).

The driving clutch member 560 has a cam portion 580 which engages a cam follower roller 582 on a pivot arm 584, said roller being held in engagement with said cam by a tension spring 586. Thus arm 584 is oscillated by cam 580 during the rotation of driving clutch member 560. An arm 588 is pivoted on the frame of the machine as indicated at 590 and projects into the pe-

ripheral slot 592 formed in the driven clutch member, the outer end of said arm 588 when depressed serving to disengage dog 572 from the driving clutch member 560 thereby to disengage the clutch. A spring 594 engages arm 588 and tends to urge the latter to retracted position. A sleeve 596 for a radially extending arm 598 integral therewith is pivotally mounted on a pin 600. Said arm has a lower weighted portion 602. A rod 604 has a slotted upper end portion 606 which is connected to lever 570 by a screw 608. The lower end of rod 604 projects through an opening 610 in the weighted lower end of arm 598. When lever 570 is moved to clutch engaging position the lower end of rod 604 is engaged by the upper end of arm 584, as illustrated in Fig. 41 and retracts the notched edge 612 of arm 598 from engagement with the plate 614 which is fixed to the upper edge of arm 588 permitting spring 594 to move arm 588 to retracted position, in which position it is ineffective to release dog 572 from driving clutch member 560.

A sleeve 616 fixed to main cam shaft 246 is provided with a pin 618 which, at the end of one revolution of the main cam shaft 246 is adapted to engage the outer end of arm 588 for moving said arm to projected position for engagement of the outer end thereof with dog 572 so that at the end of one revolution of said main cam shaft 246 the dog is retracted from the driving clutch member 560 thus disengaging the clutch. Plate 614 is provided with a slot 562 (Fig. 43A) which permits pin 618 to pass without depressing arm 588 long enough to disengage dog 572 from driving member 560, provided that lever 570 has not been moved to clutch-disengaging position. When, however, lever 570 is moved to clutch-disengaging position (Fig. 40), thereby retracting rod 604 from the path of arm 584, weighted arm 598 is no longer oscillated but can move into engagement at its notched edge 612, with plate 614 carried by arm 588 and will do so as soon as shaft 246 completes one revolution thus causing pin 618 to engage part 564 of plate 614. It will be understood that when clutch operating lever 570 is in clutch-engaging position, arm 588 is oscillated continuously and cannot depress arm 588 because the latter having been moved upwardly by spring 594, is in a position which places plate 614 above the notched edge 612 of arm 598. It will be noted further that pin 618 engages plate 614 for a very short time at the end of each revolution of shaft 246 whereby arm 588 is not depressed long enough to disengage clutch dog 572, unless rod 604 is retracted by lever 570 whereby to permit arm 598 to engage and hold plate 614 in depressed or clutch-disengaging position. Shaft 244 is connected to main cam shaft 246 by gears 620 and 622 of such ratio that shaft 244 makes four revolutions during one revolution of the main cam shaft 246. Accordingly, if lever 570 is moved to the clutch-disengaging position illustrated in Fig. 40, before one revolution of the main cam shaft 246 has occurred, thus to retract rod 604 and permit weighted arm 598 to move into engagement with plate 614 for holding arm 588 in position to disengage dog 572, the machine will continue to operate for the remainder of the cycle, that is, until one revolution of shaft 246 is completed. It is important to note that, by reason of the provision of the clutch mechanism of the construction and operation described above, the machine comes to a stop only after the band has been fully applied and the heated presser member 230 is retracted. This

5 prevents damage to many frankfurters, which would otherwise occur during daily operation of the machine, unless the frankfurters were removed by hand whenever the machine stops. In other words the heated presser member 230 is retracted from engagement with the frankfurter before the clutch is disengaged, and it is assured that when the machine stops upon disengagement of the clutch, said presser member will be 10 out of contact with the frankfurter and therefore cannot damage the frankfurter.

Summary of operation of machine

From the above description, it will be understood that the frankfurters or other articles are 15 conveyed by means of conveyor 16 to the central conveyor 20 which is intermittently operated in timed relation to conveyor 16. Said conveyor 20 carries the frankfurters successively first to the station at which the frankfurter to be banded is firmly pressed into its holder by plate 342, as 20 illustrated in Fig. 11, and from said station to the banding station in position to have bands applied thereto by the band-applying mechanism 14. From the banding station the frankfurters 25 are then moved by conveyor 20 to the station at which the presser member 298 engages the band for sealing (Fig. 31) and thereafter the banded frankfurters are carried to the receiving end of delivery conveyor 22. It will be noted that 30 presser member 298 not only holds the overlapped parts of the band while the thermoplastic adhesive sets but also holds said parts of the band together while the presser member 230 is retracted and thus prevents said presser member from pulling down the end of the band engaged thereby, which would happen due to said end of the band adhering to said presser member. The holders are automatically operated at the 35 receiving end of conveyor 20 to spread the companion relatively movable members for receiving the frankfurters therebetween, and are similarly operated at the delivery end of said conveyor to release the frankfurters and to discharge them on the delivery conveyor 22. Said delivery conveyor is positioned below the conveyor 20 whereby the frankfurters drop by gravity from the holders to the delivery conveyor.

At the banding station and in the operation 40 of the band-applying means the heater and presser 230 are operated for softening the thermoplastic coating on the bands or labels B and for pressing the overlapped end portions of the bands together in the wrapped condition. Heater and presser 230 remains in engagement with the wrapped band during the movement of the wrapped article from the banding station to a point at which the wrapped band is engaged by a holder 298. The heater and the device for moving the chains of the conveyor are at that point disengaged from the conveyor chains, and this disengagement of the heater and presser occurs just before the completion of one revolution of shaft 246, that is, just before the completion of the cycle of operations of the machine and the disengagement of the clutch, if the clutch operating lever 570 is moved to disengage the clutch. As explained above, the frankfurters are carried in sets of two by the several conveyors and are transferred by fingers 144 and 145, from the supply conveyor 16 to the article holders on conveyor 20. It will be observed that conveyor 20 is located at a higher level than conveyor 16 and that fingers 144 and 145 raise the frankfurters from the carrying members on con-

veyor 16 and transfer the same to the article holders of conveyor 20.

When the articles to be banded are at the banding station the band-applying means are operated as described above and at the same time the band feeding means operates to supply bands from the holder for the stack of bands to the band-applying means. Also, as described above the band-supplying means are ineffective to supply bands to the band-applying means unless there is a frankfurter at the delivery end of the supply conveyor 16 since, as stated above, the control valve 536 operates to cut off suction to the suction picker in the absence of the engagement of the feeler 540 with a frankfurter at the delivery end of the supply conveyor. Thus, in the operation of the machine, so long as frankfurters are supplied to conveyor 20 by supply conveyor 16 bands are fed to the band-applying means and are applied by the latter to the frankfurters in succession. To start the machine it is merely necessary to start motor M and to operate clutch lever 570 to engage the main cam shaft 246 with the driving shaft 244, and to stop the machine it is merely necessary to move lever 570 to clutch-disengaging position.

Thus it is seen that the banding machine of the present invention is well adapted to accomplish the banding of frankfurters in a practical manner and is well suited to commercial requirements. The advantages of providing frankfurters with bands will be apparent and it will be readily understood that the consumer who purchases banded frankfurters can readily identify the responsible brands and is protected against unknowingly purchasing frankfurters or other sausages of inferior quality or of unknown brands.

While we have shown and described the preferred embodiment of the invention more or less specifically, it will be understood that the invention may be embodied otherwise than as here shown and that in the illustrated embodiment described herein certain changes in the details of construction may be made. It will be understood also that although the machine is operative to band one of two linked frankfurters or other sausages, as described above, said machine is also operative to and is intended for use in banding single frankfurters or sausages which are not linked to another frankfurter or sausage, in which case the articles to be banded will be supplied as single units to the banding apparatus by conveyor chain 26 of conveyor 16 and by conveyor chains 106 and 108 of conveyor 20. Therefore, we do not wish to be limited to the invention as herein specifically shown or described except to the extent which may be required by the scope of the appended claims.

Having thus described our invention, what we claim and desire to secure by Letters Patent is:

1. In a machine of the class described, band-applying mechanism, a conveyor for moving sausages to a predetermined position, said conveyor carrying a plurality of holders for said sausages in predetermined spaced relation thereon for positively moving said sausages at a predetermined speed, and means operable in timed relation to said conveyor for transferring said sausages from said conveyor holders to a position for the application of bands thereto by said band-applying mechanism.

2. In a machine of the class described, band-applying mechanism, a movable carrier for conveying sausages to a predetermined position, said carrier comprising an endless belt having sausage

holders carried thereby in predetermined spaced relation thereon for positively moving said sausages at a predetermined speed, and means operable in timed relation to said carrier for removing said sausages from said holders on said carrier and for moving the same to a position for the application of bands thereto by said band-applying mechanism, said last mentioned means comprising means for supporting the sausages during the banding thereof.

3. In a machine for applying bands to sausages or other articles, said bands having coatings thereon rendered adhesive by the application of heat thereto, band-applying mechanism, means for moving said sausages to a position for the application of bands thereto by said band-applying mechanism, said band-applying mechanism including a device for wrapping the band around the sausage at said band-applying position with one end portion of the band extending downwardly from the sausage, and a heated member mounted below said wrapping device for movement upwardly toward and downwardly from the sausage in said last mentioned position and operative in said upward movement to move said end portion of the band upwardly and to press said end portion against the other end portion of the band and to render adhesive the coating on said first mentioned end portion for securing the band in position on the sausage.

4. In a machine of the class described, means for applying bands to sausages, means for carrying said sausages in succession to a band-applying position for the application of bands to said sausages by said band-applying means, said sausage carrying means comprising a plurality of endless belts laterally spaced from each other and holders carried by said belts in longitudinally spaced relation thereon, said band-applying means including a member movable between said belts toward and away from the sausages for pressing together the end portions of the band on the sausage.

5. In a machine of the class described, means for applying bands to sausages, means for carrying said sausages in succession to a band-applying position for the application of bands to said sausages by said band-applying means, said sausage carrying means comprising a plurality of endless belts laterally spaced from each other and holders carried by said belts in longitudinally spaced relation thereon, said band-applying means including a member movable between said belts toward and away from the sausages for pressing together the end portions of the band on the sausage, and carrying means for a plurality of sausages one of which is connected to each of said first mentioned sausage disposed laterally of said first mentioned carrying means and provided with holders for said last mentioned sausages in alignment with the first mentioned holders, respectively, said last mentioned carrying means being movable as a unit with said first mentioned carrying means.

6. In a machine of the class described, means for applying bands to sausages or the like, means for presenting to said band-applying means one of a plurality of connected sausages for application of a band to said one of said connected sausages, said last mentioned means comprising a conveyor, and holders for said plurality of connected sausages carried by said conveyor and movable therewith for moving said plurality of connected sausages in unison in presenting said

one of the connected sausages to said band-applying means.

7. In a machine of the class described, means for applying bands to sausages or the like, means for presenting to said band-applying means one sausage of each of a plurality of sets of connected sausages for application of a band to said one of said connected sausages of each of said sets, said last mentioned means comprising a conveyor, 10 holders for said sets of connected sausages carried by said conveyor and movable therewith for moving said plurality of connected sausages in unison in presenting said one of the connected sausages to said band-applying means, said holders having relatively movable parts, and means for actuating said holder parts to receive and eject, simultaneously, the plurality of connected sausages of said sets, respectively.

8. In a machine of the class described, means for applying bands to sausages or the like, means for presenting to said band-applying means one of a plurality of connected sausages for application of a band to said one of said connected sausages, said last mentioned means comprising a conveyor having a plurality of laterally spaced 15 endless belts, holders for the sausages carried by said belts in spaced relation longitudinally thereof, and means movable between certain of said belts toward and away from the sausage to which the band is applied for engagement with the applied band for the purpose of pressing together the end portions thereof.

9. In a machine of the class described provided with means for applying bands to articles, means for conveying said articles in succession to a position at which the bands are applied thereto, said means comprising a movable conveyor provided with article gripping members, there being two pairs of relatively movable companion gripping members for each article to be banded, said two pairs of gripping members being spaced from each other and positioned to engage the article at points spaced longitudinally of the latter and said band-applying means including a wrapping device positioned above said conveyor and including band-wrapping parts movable downwardly from a retracted position to a projected position between said two pairs of gripping members for wrapping the band around the part of the companion article in the space between said pairs of gripping members, means for moving said conveyor intermittently for presenting the articles in succession to said band-applying means, and means for actuating said band-applying means.

10. In a machine of the class described provided with means for applying bands to articles, means for conveying said articles in succession to a position at which the bands are applied thereto, said means comprising a movable conveyor provided with article gripping members, means for moving said conveyor intermittently for presenting the articles in succession to said band-applying means, and a continuously movable conveyor for supplying the articles to said intermittently operable conveyor, and means operated under the control of said intermittently operable conveyor for transferring said articles in succession from said continuously movable conveyor to said intermittently operable conveyor.

11. In a machine of the class described provided with means for applying bands to articles, means for conveying said articles in succession to a position at which the bands are applied thereto, said means comprising a movable conveyor provided with article gripping members,

means for moving said conveyor intermittently for presenting the articles in succession to said band-applying means, a continuously movable conveyor for supplying the articles to said intermittently operable conveyor, and means operated under the control of said intermittently operable conveyor for transferring said articles in succession from said continuously movable conveyor to said intermittently operable conveyor, and means for preventing movement of said intermittently movable conveyor during the band-applying operations of said band-applying means.

12. In a machine of the class described provided with means for applying bands to articles, means for conveying said articles in succession to a position at which the bands are applied thereto, said means comprising a movable conveyor provided with article gripping members, means for moving said conveyor intermittently for presenting the articles in succession to said band-applying means, means for holding the conveyor stationary when the bands are being applied to said articles, a continuously movable conveyor for supplying the articles to said intermittently operable conveyor, and means operable between the intermittent movements of said first mentioned conveyor for transferring the articles from said supply conveyor to said gripping members on said first mentioned conveyor.

13. In a machine of the class described, means for applying bands to articles comprising a device for wrapping the bands around the articles and means for pressing overlapped portions of the bands together on the articles, respectively, 35 said pressing means comprising a member movable toward and away from said articles, intermittently movable means for presenting said articles in succession to said wrapping device and for moving the band-wrapped articles therefrom with an intervening rest period during the wrapping operation, means for moving said pressing means while in engagement with said portions of the wrapped-band during a part of the movement of the wrapped article away from said 45 band-wrapped device and in the direction of said movement of the band-wrapped article, and means releasably interconnecting said last mentioned means with said intermittently movable means for unitary movement thereof.

14. In a machine of the class described, means for applying bands to articles comprising a device for wrapping the bands around the articles and means for pressing overlapped portions of the bands together on the articles, respectively, 55 said pressing means comprising a member movable toward and away from said articles, intermittently movable means for presenting said articles in succession to said wrapping device and for moving the band-wrapped articles therefrom with an intervening rest period during the wrapping operation, means for moving said pressing means while in engagement with said portions of the wrapped-band during a part of the movement of the wrapped article away from said band-wrapping device and in the direction of said movement of the band-wrapped article, means releasably interconnecting said last mentioned means with said intermittently movable means for unitary movement thereof, said pressing means having a return movement for engagement with similar portions of the next wrapped-band, and means engageable with the previously pressed end portions of the band for holding them pressed together after they are released by said first mentioned pressing means.

15. In a machine of the class described, means for applying bands to articles comprising a device for wrapping the bands around the articles with one end portion of the band extending downwardly from the companion article, said band-applying means including also means for pressing overlapped portions of the bands together on the articles, respectively, said pressing means comprising a member mounted below said band-wrapping device for movement upwardly toward and downwardly away from said articles and operative in said upward movement to move said end portion of the band upwardly and to press said end portion against the other end portion of the band, intermittently movable means for presenting said articles in succession to said wrapping device and for moving the band-wrapped articles therefrom with an intervening rest period during the wrapping operation, said last mentioned means comprising a conveyor provided with holders for said articles, and means operable in timed relation to the operation of said band-wrapping device and said pressing means for imparting said intermittent movement to said conveyor.

16. In a machine of the class described, means for applying bands to articles comprising a device for wrapping the bands around the articles with one end portion of the band extending downwardly from the companion article, said band-applying means including also means for pressing overlapped portions of the bands together on the articles, respectively, said pressing means comprising a member mounted below said band-wrapping device for movement upwardly toward and downwardly away from said articles and operative in said upward movement to move said end portion of the band upwardly and to press said end portion against the other end portion of the band, intermittently movable means for presenting said articles in succession to said wrapping device and for moving the band-wrapped articles therefrom with an intervening rest period during the wrapping operation, said last mentioned means comprising a conveyor provided with holders for said articles, and means for moving said presser means as a unit in engagement with the wrapped article on said conveyor during part of the movement of said conveyor.

17. In a machine of the class described, means for applying bands to articles comprising a device for wrapping the bands around the articles with one end portion of the band extending downwardly from the companion article, said band-applying means including also means for pressing overlapped portions of the bands together on the articles, respectively, said pressing means comprising a member mounted below said band-wrapping device for movement upwardly toward and downwardly away from said articles and operative in said upward movement to move said end portion of the band upwardly and to press said end portion against the other end portion of the band, intermittently movable means for presenting said articles in succession to said wrapping device and for moving the band-wrapped articles therefrom with an intervening rest period during the wrapping operation, said last mentioned means comprising a conveyor movable in one direction provided with holders for said articles, means operable in timed relation to the operation of said band-wrapping device and said pressing means for imparting said intermittent movement to said conveyor, and

means for thereafter withdrawing said presser member from said article and for moving said presser member in a direction opposite to said one direction of movement of said conveyor whereby to dispose said presser member in a position below the next article to be banded in the band-applying position.

18. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor and operable in timed relation thereto for transferring the sausages in succession from said supply conveyor to the holders on said first mentioned conveyor at said receiving end thereof.

19. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the holders on said first mentioned conveyor at said receiving end thereof, said last mentioned means comprising fingers movable in timed relation to the movements of both of said conveyors from a lower position, for engaging the sausages on said supply conveyor, to a higher position for lifting the sausages from said supply conveyor and for transferring them to said holders in position between said companion holder members, respectively.

20. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor and operable in timed relation thereto for transferring the sausages in succession from said supply conveyor to the holders on said first mentioned conveyor at said receiving end thereof, said first mentioned conveyor being movable intermittently and being stationary during the

transfer of the sausages thereto from said supply conveyor by said transferring means.

21. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the holders on said first mentioned conveyor at said receiving end thereof, said first mentioned conveyor being movable intermittently and being stationary during the transfer of the sausages thereto from said supply conveyor by said transferring means, and means for actuating said band-applying means while said first mentioned conveyor is stationary for applying a band to the sausage in the holder presented thereto by said first mentioned conveyor.

22. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the holders on said first mentioned conveyor at said receiving end thereof, said relatively movable members of each of said holders being operable at the delivery end of said first mentioned conveyor to move away from each other for releasing the sausage, each of said holders being movable from a horizontal position to a vertical position at the delivery end of said first mentioned conveyor for discharging the sausage therefrom.

23. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the holders on said first mentioned conveyor at said receiving end thereof, said last mentioned means comprising fingers movable in timed relation to

5 the movements of both of said conveyors from a lower position, for engaging the sausages on said supply conveyor, to a higher position for lifting the sausages from said supply conveyor and for transferring them to said holders in position between said companion holder members, respectively, and means operable above said first mentioned conveyor for engaging the upper surfaces of said sausages in said holders and pressing the same downwardly between said companion holder members, respectively, before said sausages are presented to said band-applying means.

15 24. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of 20 relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the 25 holders on said first mentioned conveyor at said receiving end thereof, said first mentioned conveyor being movable intermittently and being stationary during the transfer of the sausages thereto from said supply conveyor by said transferring means, and means operable above said first mentioned conveyor while the latter is stationary for engaging the upper surfaces of said sausages in said holders and pressing the same downwardly between said companion holder members, respectively, before said sausages are presented to said band-applying means.

30 25. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of 35 relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the 40 holders on said first mentioned conveyor at said receiving end thereof, said first mentioned conveyor being movable intermittently and being stationary during the transfer of the sausages thereto from said supply conveyor by said transferring means, and means operable above said first mentioned conveyor while the latter is stationary for engaging the upper surfaces of said sausages in said holders and pressing the same downwardly between said companion holder members, respectively, before said sausages are presented to said band-applying means.

45 26. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of 50 relatively movable members operable at the receiving end of the conveyor to move away from each other for receiving the sausage therebetween and operable thereafter to move toward each other for gripping the sausage therebetween, a supply conveyor for delivering the sausages to the receiving end of said first mentioned conveyor, means at the receiving end of said first mentioned conveyor for transferring the sausages in succession from said supply conveyor to the 55 holders on said first mentioned conveyor at said receiving end thereof, said first mentioned conveyor being movable intermittently and being stationary during the transfer of the sausages thereto from said supply conveyor by said transferring means, means operable above said first mentioned conveyor while the latter is stationary for engaging the upper surfaces of said sausages in said holders and pressing the same downwardly between said companion holder members, respectively, before said sausages are presented to said band-applying means, and means for actuating said band-applying means while said first mentioned conveyor is stationary for applying a band to the sausage in the holder presented thereto by said first mentioned conveyor.

60 27. In a machine of the class described, band-

65

70

75

applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, and means operable in timed relation to the movement of said conveyor for engaging the sausages in said holders and for pressing them downwardly between said companion holder members, respectively, before said sausages are presented to said band-applying means.

27. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, said relatively movable members of each of said holders being operable at the delivery end of said conveyor to move away from each other for releasing the sausage, each of said holders being movable from a horizontal position to a vertical position at the delivery end of said conveyor for discharging the sausage therefrom.

28. In a machine of the class described, band-applying means, a conveyor for moving sausages in succession to present the same to said band-applying means for the application of bands thereto, a plurality of sausage holders carried by said conveyor in longitudinally spaced relation thereon, each of said holders comprising a pair of relatively movable members operable at the receiving end of the conveyor to move away from each other for receiving the sausage therebetween and operable thereafter to move toward each other for gripping the sausage therebetween, said relatively movable members of each of said holders being operable at the delivery end of said conveyor to move away from each other for releasing the sausage, each of said holders being movable from a horizontal position to a vertical position at the delivery end of said conveyor for discharging the sausage therefrom, and a discharge conveyor positioned below said first mentioned conveyor for receiving the sausages discharged from said holders.

29. In a machine of the class described, a band-applying mechanism, a conveyor for moving articles in succession to a position for the application of bands thereto by said mechanism, a frame carrying said mechanism and movable toward and away from said articles for operatively engaging the banding mechanism with said articles in succession, holders for said articles carried by said conveyor, and means movable toward and away from said holders to engage said articles in succession prior to the movement thereof to said position for forcing said articles firmly in position in their respective holders.

30. In a machine of the class described, a band-applying mechanism, a conveyor for moving articles in succession to a position for the application

of bands thereto by said mechanism, a frame carrying said mechanism and movable toward and away from said articles for operatively engaging the banding mechanism with said articles in succession, holders for said articles carried by said conveyor, means movable toward and away from said holders to engage said articles in succession prior to the movement thereof to said position for forcing said articles firmly in position in their respective holders, said last mentioned means including a presser plate, and resilient means for applying pressure to said plate when the latter is in engagement with the article in the holder therefor.

31. In a machine of the class described, means for applying bands to sausages or the like, means for presenting to said band-applying means one of a plurality of connected sausages for application of a band to said one of said connected sausages, said last mentioned means comprising a conveyor having a plurality of laterally spaced endless belts, holders for the sausages carried by said belts in spaced relation longitudinally thereof, said laterally spaced belts being mounted for relative movement toward and away from each other, and means for moving one of said belts toward and away from another of said belts.

32. In a machine of the class described, means for applying bands to sausages or the like, means for presenting to said band-applying means one of a plurality of connected sausages for application of a band to said one of said connected sausages, said last mentioned means comprising a conveyor having a plurality of laterally spaced endless belts, holders for the sausages carried by said belts in spaced relation longitudinally thereof, a supply conveyor for delivering sausages to said first mentioned conveyor, said supply conveyor comprising a plurality of laterally spaced endless belts, said laterally spaced belts of each of said conveyors being mounted for relative movement toward and away from each other, and means for moving one of the belts of each of said conveyors toward and away from another of said belts thereof.

33. In a machine of the class described, means for applying bands to sausages or the like, means for presenting to said band-applying means one of a plurality of connected sausages for application of a band to said one of said connected sausages, said last mentioned means comprising a conveyor having a plurality of laterally spaced endless belts, holders for the sausages carried by said belts in spaced relation longitudinally thereof, a supply conveyor for delivering sausages to said first mentioned conveyor, said supply conveyor comprising a plurality of laterally spaced endless belts, said laterally spaced belts of each of said conveyors being mounted for relative movement toward and away from each other, and means for moving one of the belts of one of said conveyors and one of the belts of the other conveyor simultaneously toward another of the belts of the same conveyors, respectively.

34. In a machine for applying bands to sausages or other articles, said bands having coatings thereon rendered adhesive by the application of heat thereto, band-applying mechanism, a heated member movable into engagement with a part of the applied band for rendering the coating thereof adhesive and for pressing said part of the band against another part thereof, said heated member being thereafter movable to a retracted position out of contact with said band, and means for holding said first mentioned part of the band in

position during the movement of said heated member to retracted position and for a predetermined period of time thereafter whereby to prevent said first mentioned part of the band from being withdrawn by the retractive movement of said heated member and to hold said first mentioned part of the band in position until the adhesive has set.

35. In a machine for applying bands to sausages or other articles, said bands having coatings thereon rendered adhesive by the application of heat thereto, band-applying mechanism, a conveyor for moving sausages to a predetermined position, means for transferring said sausages from said conveyor to a position for the application of bands thereto by said band-applying mechanism, and a heated member temporarily engageable with the applied band to render the coating thereof adhesive for securing the band in position on the sausage, said heated member being thereafter movable to a retracted position out of con-

tact with the applied band, and means for preventing separation of parts of the band by said retractive movement of the heated member.

36. In a machine for applying bands to sausages or other articles, said bands having coatings thereon rendered adhesive by the application of heat thereto, band-applying mechanism, a conveyor for moving sausages to a predetermined position, means for transferring said sausages from said conveyor to a position for the application of bands thereto by said band-applying mechanism, a heated member temporarily engageable with the applied band to render the coating thereof adhesive for securing the band in position on the sausage, and means including a one revolution clutch for operating the machine, said heated member being movable to retracted position out of contact with the banded frankfurter before disengagement of said clutch.
